(57) **CLAIM**

The ornamental design for a bottle, as shown and described.

DESCRIPTION

FIG. 1 is a perspective view of a bottle showing my new design;

FIGS. 2-4 are side elevation views thereof;

FIG. 5 is a top plan view thereof; and,

FIG. 6 is a bottom plan view thereof.

The broken line showing of a bottle in FIG. 6 is included for the purpose of illustrating only and forms no part of the claimed design.

1 Claim, 4 Drawing Sheets
